CONTINUOUS CENTRIFUGAL SEPARATOR
AND CLARIFIER

Andrew F. Howe, University City, Mo., assignor to
B H and M Company, St. Louis, Mo., a corpora-
tion of Missouri

Application March 5, 1937, Serial No. 129,144

3 Claims. (Cl. 233—7)

This invention relates to continuous centrifugal separators and clarifiers, and has special reference to separators and clarifiers for use in detaching solids and the like from fluids in which they are sustained or immersed.

An object of the invention is to provide a separator and clarifier for detaching or separating solids from fluids and for discharging the solids through one outlet from the separator and the fluids through another outlet from the separator, so that the discharged fluids will be nearly free from any solids even though the solids remain in the separator during the discharge of the clarified fluid therefrom.

Another object of the invention is to provide an improved centrifugal separator and clarifier including a rotary bowl into which the mixture of fluids and solids is delivered while the bowl is in rapid rotation, and to provide rotary mechanism in the bowl for causing the solids to deposit upon a detachable bottom closing the lower end of the bowl while the clarified fluid flows from the bowl through an opening at the top thereof, and to provide means for opening the bottom of the bowl from time to time to discharge the solids therefrom.

Another object of the invention is to provide improved means for rotating the bowl and the device for settling the solids at varying speeds so as to cause the mechanism to function properly by discharging clarified fluid from the top of the bowl and the detached or separated solids from the bottom of the bowl.

Other objects will be apparent from the following description, reference being made to the annexed drawing, in which—

Fig. 1 is a vertical sectional view of a centrifugal separator and clarifier embodying the features of the present invention.

Fig. 2 is an outer side elevation of a portion of the driving or operating mechanism.

Fig. 3 is a plan view of a part of the mechanism that is illustrated in Fig. 2.

Fig. 4 is a detail sectional view of a part of the electrical control mechanism illustrated in Figs. 2 and 3.

The specific embodiment of the invention illustrated comprises a rigid supporting frame 1, which may be a housing having substantially imperforate walls forming an enclosure into and through which the detached solids are discharged.

The housing has an outlet passage 2 through which the clarified fluids which were included in the original mixture of solids and fluids are discharged after the solids and fluids have been

separated. The housing includes a number of webs 3 supporting a central journal member 4. A tubular shaft 5 is journaled in vertically spaced bearings 6 and 7 within the journal member 4 and supported by shoulders 8 and 9 formed within said journal member 4. The upper end of the shaft 5 is attached by fasteners 10 to a horizontal wall portion 11 attached to the lower end of a receiving bowl 12 by bolts or otherwise. A number of outlet openings 13 are formed through the wall 11. An annular flange 14 integral with the wall 11 seats upon the upper end of the journal member 4.

A movable bottom wall or valve 15 has a central opening through which the upper end of the tubular shaft 5 extends, and said wall supports in its upper side an annular gasket 16 movable into contact with an annular flange 17 formed within the lower portion of the bowl 12 so as to close the lower end of said bowl, and is movable downwardly toward the wall 11 and out of contact with the flange 17 in order to open the lower end of the bowl and permit the detached and deposited solids to be discharged centrifugally through the openings 13 into the housing frame 1. The valve wall 15 is connected with the bowl wall 11 by guide pins 18 attached to the wall 11 and extending upwardly through holes in the valve wall 15 to permit vertical sliding movements of said valve wall.

An electro-magnet 19 has its armature 20 pivotally connected with the underside of the valve wall 15 and is moved upwardly when the electro-magnet is energized, and is movable downwardly by gravity and by the weight of the valve wall 15 and the solids or substances supported thereby so as to move said valve wall out of contact with the flange 17 to provide an opening at the bottom of the bowl 12 through which the solids are discharged centrifugally from the bowl 12. The electric circuit wires 21 and 22 lead to the electro-magnet through a housing 23 mounted in the frame 1 and through the journal member 4, and thence through an opening in the flange 14 to connection with the electro-magnet 19. A shaft 24 extends through the tubular shaft 5 and is supported by a bearing 25 mounted on the upper end of said shaft 5. A wall 26 is attached to the upper end of the shaft 24 within the bowl 12 and above the valve wall 15 and cooperates with the wall of the bowl 12 to form a radially narrow space 26' providing a passage for the movement of the solids downwardly onto the wall 15 and toward the outlet openings 13.

A unit comprising a tube 27, a flange 28 in-

tegral with the lower end of said tube, and a conical series of flights 29 integral with the tube 27 and the flange 28, is mounted on and attached to the wall 26 by removable and replaceable fasteners 30. The lower ends of the flights 29 operate close to the inner surface of the bowl 12 and extend through the narrow annular passage 28' between the wall of the bowl 12 and the edges of the wall 26 and the flange 28. As shown, the wall 26 and the flange 28 are of less diameter than the internal diameter of the bowl 12, thereby providing the narrow passage 28' through which the solids may pass downwardly onto the valve wall 15.

15 A funnel hopper 31 is supported by and extends through an opening in the upper wall of the lid 32 and downwardly into the upper end of the tube 27 for the purpose of conducting the fluids and the solids contained therein into the tube 27, from which the fluids and the solids are discharged into the bowl 12 through openings 33 at the lower end of the tube 27.

20 The upper end of the bowl 12 is provided with a wall 34 separated from an inner wall 35 by a space 36, from which space passages 37 open to the outside of the bowl 12 for the discharge of the clarified fluids into the space 38 communicating with the outlet passage 2. The wall 35 is formed with a large central opening 39 communicating with the space 36 and the wall 34 is formed with a smaller opening 40. Thus, the inner margin of the wall 34 extends inwardly beyond the inner margin of the wall 35, and constitutes a baffle for deflecting at least a considerable portion of the clarified fluids into the space 36 and thence through the passages 37 into the receiving space 38. However, whenever all of the clarified fluids cannot pass through the space 36 and the passages 37, the remaining portion thereof may pass through the opening 40 into the space 38.

25 A drive pulley 41 is attached to the shaft 5 and a separate drive pulley 42 is attached to the shaft 24, so that said shafts may be rotated independently and at different speeds. A motor 43 has its shaft 44 attached to pulleys 45 and 46 provided with driving connections 47 and 48 to the pulleys 41 and 42, respectively, so that said pulleys may be rotated at different speeds by the motor. A disc 49 is rotative on an axis 50 and has an arcuate metallic contact member 51 attached thereto provided with a space 52 between its ends, and is rotated about said axis by driving connections including a friction disc 53 mounted on an axle 54 rotated by a worm pinion 55 so that, when the pinion 55 is rotated, the disc 49 will be rotated. Contact members 56 and 57 are pressed against the arcuate contact member 51 by springs 58 and 59, respectively, from which the wires 21 and 22 lead so that, as the disc 49 is rotated, the circuit to the electro-magnet is automatically opened and closed, being opened when the contact members 56 and 57 are out of engagement with the arcuate contact member 51, and being closed when said contact members 56 and 57 are in contact with said arcuate contact member 51. Thus, when the contact members 56 and 57 are out of engagement or contact with the arcuate contact member 51, electrical energy to the electro-magnet 19 is stopped, said electro-magnet becomes unenergized, and the valve plate 15 drops downwardly from the flange 16 and separated therefrom by an intervening space through which the solids settled or deposited in the bowl

12 are discharged outwardly through the openings 13.

The specific construction and arrangement of this electrical device is unimportant and may be varied as widely as possible without departure from the nature and principle of the invention. Also, the connections 60 for varying the relative speeds of rotation of the pulleys 45 and 46 may be varied since said connections are known and specific description thereof in connection with the present invention is unnecessary.

This entire mechanism is capable of continuous operation and is operative to separate liquids of different weights from each other and to clarify the respective liquids by separating the solids therefrom. For instance, in the specific embodiment of the invention shown, if a mixture of liquids of different weights is to be separated and clarified and the separated and clarified liquids discharge separately, the heavier liquid will pass through the outlet space 36 and may be conducted therefrom to any point of delivery, and the lighter liquid discharged through the outlet 40 and conducted therefrom to any separate point of delivery. The specific means for conducting the separated and clarified liquids to different points of delivery is not shown and any appropriate conduits for that purpose may be provided.

Additionally, the separator is kept in a clean condition because of the flow of the separated and clarified liquids upwardly and the discharge downwardly of the solids even if a small amount of liquid adheres to the solids. Because of the capacity to separate and clarify mixtures of liquids of different weights and to maintain the machine in continuous operation and in a permanently cleaned condition, this machine is of great advantage.

From the foregoing, it will be apparent that my invention comprises a rotary solid bowl 12 having therein rotary mechanism 29, etc. with a communicating passage 27, through which the mixed solids and liquids may be conducted into the bowl. Since the bowl 12 and the mechanism 29, etc. rotate at different or differential speeds, the solids will be moved downwardly and deposited upon the valve plate 15, and the clarified liquid will be discharged upwardly and outwardly through the opening 39 and the space 36; or, if necessary, will be partially discharged through the opening 40 into the space 38 and thence through the outlet opening 2. The mechanism for rotating these bowls at the differential speeds desired to effect the separation of the solids from the liquids and to clarify or purify the liquids may be varied as widely as permissible within the scope of the equivalent limits without departure from the nature and principle of the invention. And the separating mechanism comprising the bowl 12 and the separate rotating devices 29 may also be varied without departure from the invention.

I claim:

1. A centrifugal separator comprising a bowl rotative about a vertical axis and having an opening through the top for the discharge of fluids by centrifugal action and having an outlet passage through the bottom for the discharge of solids by centrifugal action, rotary means in the bowl forming a narrow passage for the downward movement of solids toward said outlet passage, a tube in said bowl supported by said rotary means for conducting mixed fluids and solids into the lower portion of the bowl for centrifugal separa- 75

tion, elements supported by said tube and extending downwardly through said second passage for discharging the solids downwardly through said second passage toward said outlet passage, and mechanism for controlling the flow of solids toward said outlet opening.

2. A centrifugal separator comprising a bowl supported for rotation about a vertical axis and having an opening through the top for the discharge of fluids by centrifugal action and having an outlet passage through the bottom for the discharge of solids by centrifugal action, a tube in said bowl for conducting mixed fluids and solids into the lower portion of the bowl and having an opening near its lower end for the passage of said fluids and solids into said bowl for centrifugal separation, a rotary wall element below said opening from said tube supporting said tube and having its margin separated from the wall 20 of said bowl by a relatively narrow space for the passage of solids to said outlet passage, downwardly diverging flights having their upper ends attached to said tube and extending downwardly through said space beyond the lower end of said tube, a device for controlling the passage of solids from said space toward said outlet passage, mech-

anism for operating said device intermittently during the rotation of the bowl alternately to permit and prevent passage of solids to said outlet passage, an operating machine, and mechanisms operated by said machine for rotating said bowl and said tube, respectively, and thereby said flights.

3. A centrifugal separator comprising a bowl supported for rotation about a vertical axis and having oppositely disposed passages for the discharge of fluids and solids respectively, a rotary element in said bowl forming a narrow passage for the downward movement of solids toward the passage for discharge of solids, a tube for conducting mixed fluids and solids into said bowl, a series of downwardly diverging flights attached to said tube and extending downwardly through said narrow passage, a device in said bowl between said narrow passage and said outlet passage for solids controlling intermittent discharge 20 of solids from said bowl during rotation of said bowl and said flights, and mechanisms for rotating said bowl and said flights, respectively, at differential speeds.

ANDREW F. HOWE.
